Walter Soderling, Inventor,

By his attorneys,

Emery, Booth, Jamney & Varney

UNITED STATES PATENT OFFICE.

WALTER SODERLING, OF READING, PENNSYLVANIA, ASSIGNOR, BY MESNE ASSIGNMENTS, TO WILLSON GOGGLES, INC., OF READING, PENNSYLVANIA, A CORPORATION OF PENNSYLVANIA.

MOLDED DEVICE.

1,382,865.

Specification of Letters Patent. Patented June 28, 1921.

Application filed April 1, 1918, Serial No. 225,890. Renewed November 27, 1920. Serial No. 426,878.

To all whom it may concern:

Be it known that I, WALTER SODERLING, a citizen of the United States, and a resident of Reading, in the county of Berks and State 5 of Pennsylvania, have invented an Improvement in Molded Devices, of which the following is a specification.

This invention relates to molded articles, and with regard to certain more specific 10 features, to a support for a telephone transmitter and method of supporting a transmitter.

Among the several objects of the invention may be noted the provision of a convenient 15 and inexpensive holder for a transmitter, so constructed as to exclude extraneous sounds and yet in no way impede the wearer's breathing; and the provision of a method for supporting the transmitter in 20 such a way as to permit the wearer to speak into the transmitter without requiring the use of either of his hands, and at the same time to exclude extraneous sounds from the transmitter. Other objects will be in part 25 obvious and in part pointed out hereinafter.

The invention accordingly consists in the features of construction, combinations of elements, steps and sequence of steps, and arrangement of parts which will be exemplified in the structure hereinafter described and the scope of the application of which will be indicated in the accompanying claims.

In the accompanying drawings, in which 35 is shown one of various possible embodiments of this invention,

Figure 1 is a front elevation of the article itself.

Fig. 2 is a front elevation of the article, 40 showing a transmitter and band associated therewith as the several parts appear when in use.

Fig. 3 is a side elevation of Fig. 2.

Fig. 4 is a longitudinal vertical section.

45 Similar reference characters refer to corresponding parts throughout the several views of the drawings.

Referring now to the accompanying drawings, there is illustrated at 1 a molded article, 50 in this case of rubber, made in a single piece and comprising two portions. The rear portion 3 is approximately triangular in cross-section and tapers outwardly toward the rear and terminates preferably in a thin

or feather-edge 4 of such contour that it 55 adapts itself readily to the features of the wearer, a recess 6 being provided at the top to fit about the wearer's nose, the lower edge 7 fitting preferably between the wearer's mouth and chin, as indicated diagrammatically in Figs. 2 and 3. The front end of this rear portion comprises a vertical plane or flange member 9, covering the entire front surface of this rear portion except for a round aperture 11 communicating with the 60 front portion 13 of the article. This front portion is approximately cylindrical in shape, with a diameter somewhat larger than the aperture 11, and is provided with a plane or flange member 14 at its front or outer 65 surface. This front flange 14 is apertured as at 16 and extends outwardly beyond the outer surface of the cylindrical part 13, to an approximately elliptical shape, and is pierced as at 19, for a purpose hereinafter 70 described. The aperture 16 in this flange is smaller than the inner diameter of the cylindrical part 13, but is larger than the diameter of the aperture 11.

The front portion of the article is shaped 80 to receive a telephone transmitter, of any suitable type, and the exact contour of the front portion varies naturally according to the dimensions of the transmitter with which it is intended to be used. The embodiment 85 of the article that is illustrated in the drawings is proportioned to receive a transmitter of a flat cylindrical shape, and the aperture 16 at the front of the article is large enough and the flange 14 flexible enough, so that the 90 transmitter can be inserted and removed through this aperture. The inner aperture 11, however, is small enough to prevent the transmitter from passing therethrough. When the transmitter, which is indicated conventionally at 21 in Figs. 2 and 3, is placed 95 in position within the cylindrical part 17 of the front portion, a plate or other retaining device 23 is applied to the outer flange 14 and secured thereto by screws or buttons 25 passing through the holes 19 in the flange, an aperture 24 in the plate permitting egress of the wires leading from the transmitter. The shape of the flange 14 is preferably 100 similar to the shape of the plate 23 associated therewith, and in the present instance both the plate and the flange are illustrated 105 as elliptical in contour.

The article is secured to the wearer's head by suitable means, such as a band 26 passing around the head and attached to the device as by means of buttons or screws 27 fixed in the rear portion 3. The article is thus readily removable from the wearer's head and can be applied or taken off at a moment's notice.

Inasmuch as the article fits fairly closely to the wearer's face and preferably is substantially air-tight, the apertures 29 are provided in the rear portion 3 to permit the entrance and exit of air for breathing, without, however, admitting extraneous noises to an extent that would disturb the clearness of transmission of the wearer's voice to the telephone circuit. The apertures 29 are of proper size to insure breaking up of sound vibrations that would interfere with the transmission of the wearer's voice to the transmitter.

An additional aperture in the rear portion 3 may be provided to supply a suitable gas to the wearer in addition to air.

An absorbent material is preferably provided at the rear of the transmitter to prevent moisture reaching the transmitter, and around the inside of the rear portion 3 to absorb moisture of the breath.

It will thus be seen that the several objects of the invention are achieved, and other advantageous results attained.

As many changes could be made in the above construction and many apparently widely different embodiments of this invention could be made without departing from

the scope thereof, it is intended that all matter contained in the above description or shown in the accompanying drawings shall be interpreted as illustrative and not in a limiting sense.

I claim:

1. A molded article having a flaring portion adapted to fit about the nose and mouth, the walls thereof converging in a forward direction and terminating in an aperture, a second portion integral with the first and adapted to contain a telephone transmitter, the diaphragm of the transmitter registering substantially with the aperture in the first portion whereby the voice of the wearer is confined within the first portion and directed toward said diaphragm to the exclusion of extraneous sounds, the second portion being provided with an outer flange smaller than the transmitter but sufficiently flexible to permit the insertion and removal of the transmitter therethrough, and means secured to the outside of said flange to retain the transmitter in position.

2. A molded article combining a portion adapted to fit the nose and mouth and having a feather or tapered edge to fit closely to the wearer's face, a portion adapted to hold a telephone transmitter, and absorbent material positioned to absorb moisture of the breath, and to prevent moisture reaching the transmitter.

In testimony whereof I have signed my name to this specification this 29th day of March, 1918.

WALTER SODERLING.
